UNITED STATES PATENT OFFICE.

JANG LANDSING, OF BROOKLYN, NEW YORK.

ELECTRIC RAIL-BOND.

SPECIFICATION forming part of Letters Patent No. 755,889, dated March 29, 1904.
Application filed April 25, 1900. Serial No. 14,846. (No model.)

To all whom it may concern.

Be it known that I, JANG LANDSING, a citizen of the United States, residing in the borough of Brooklyn, in the city of New York, in the county of Kings and State of New York, have invented a new and useful Improvement in Electric Rail-Bonds, of which the following is a specification.

This invention, which relates to conductively connecting the abutting ends of rails, has for its object the production of an electric bond of continuity of material, of transversal and longitudinal elasticity, and of permanency in contact between bond and rail.

The bond manufactured according to the present invention is of homogeneous metal throughout its length and combines the greatest longitudinal and transversal elasticity with the largest cross-sectional area admissible between the fish-plate and the rail-web.

In the accompanying drawings, forming a part of the present application, Figures 1 to 6 illustrate the consecutive steps in producing one form of a contact-terminal, of which Figs. 7 and 8 are plan views. Figs. 9 to 13 illustrate the consecutive steps of one way of producing longitudinal and transversal flexibility. Figs. 14 to 16 are plan views of different forms of bonds. Fig. 17 is a modification of the connecting-piece; and Fig. 18 is a longitudinal section of the ends of the adjoining rails, together with the fish-plates and a bond in position.

The process in a general way consists of three main steps: first, producing the terminals; second, dividing the body portion, and, third, imparting longitudinal and transversal elasticity to the body portion.

In the process of manufacture a bar of commercial conducting material—for instance, rolled copper—is reduced in thickness at its ends *a* to facilitate the formation of the terminals. If solid attaching-terminals should be desired, the same may be made by any process known in the art. A shallow impression *b* is then made concentric with but of larger diameter than the desired terminal. The depth of this impression is now increased, *c*, and its diameter decreased, and this operation may be repeated until a desired length and diameter of

the terminal are obtained. An aperture *d* is then produced into the bottom portion of the depression and the remaining metal *f* of the bottom pressed down and outwardly, so as to increase the length and complete the formation of the terminal. The remaining shoulder *g* of the terminal may be of any suitable shape. The body portion *h* of the bond between the terminals is then divided into a series of longitudinal elements. It is obvious that this operation of dividing may be done before or after the formation of the terminals. The next step is to decrease the distance between the terminals by suitably bending the elements of the connecting portion and then separating one of the elements *i*, as shown in Fig. 11. In this element *i* a bend or loop *k*, resembling the letter **S**, is now formed, Fig. 12, which is done without further reducing the distance between the terminals. It is not of the essence of this invention to place this loop *k* at or near the terminal, and any desired distance from the same may be chosen, nor is it necessary to form this loop exactly like an **S**. Any other shape, as in Fig. 17, capable of being stretched or pressed longitudinally or transversally will answer the same purpose. A second element *j* is now provided with a similar loop *m*, adjoining the one, *k*, in element *i*, and therefore at a different distance from the terminal. After all the elements are bent in the required shape the bond *G* will appear as illustrated in Fig. 14, and it is readily seen that the bond possesses edge-wise as well as longitudinal elasticity and flexibility, which, although far in excess of that required by the expansion and contraction of the abutting rails, is produced in a bond of such compactness so as to be placed between the fish-plate and the rail-web and at the same time having the greatest possible cross-section to carry the current required in starting a heavy train. The elasticity is so great there is absolutely no danger of strain on any of the parts or the pulling loose of the contact-terminals from the rail, and thereby creating resistance and decreasing conductivity.

The relation of the loops in the single elements, which elements each may consist of

one or more straight portions and one or more loops, is characterized by their different longitudinal positions.

If the coordinate x is parallel to the longitudinal axis of the bond and coordinate y at right angles thereto in the plane of the bond, then all the axes of all the other loops in all the elements must be parallel to respectively, but at predetermined distances from, 10 each other.

The loops may be arranged in groups near the terminals, so as to leave space, if necessary, for the screw-bolts holding the fish-plates.

Fig. 18 illustrates the meeting ends M N of 15 two rails, against which on one side is applied a rail-bond G, the joint being completed by the fish-plate n n, secured to the rails by the usual bolts, the bond G being between the rails and one of the fish-plates.

20 Whatever stress or strains due to the expansion or contraction of the rails will be received and transmitted by the bond in direct line with the centers of the terminals, which fact tends to greatly insure the continuity of 25 contact between bond and rail.

What I claim, and desire to secure by Letters Patent, is—

1. In an electric rail-bond having several looped connecting elements and in combination with the ends of two adjacent rails, the improvement, which consists in the loops of the separate elements being bent out of the general direction of the elements, being also located outside of each other or unnested, and 30 being arranged at progressively-varying distances from the ends of the bond so as to extend in a substantially oblique line relatively to one side of the bond, the intermediate loops being, with respect to the length of the bond, 35 located each between two loops, substantially as set forth.

2. An electric rail-bond comprising several connecting elements, each of which extends longitudinally in a general direction parallel 40 with the others and all of which are in sub-

stantial contact, but the end portions of each of which elements are out of alignment, and each of which has a loop between said end portions, said loops being severally spaced and arranged to form a series, each loop thereof occurring at a different point along the element with respect to the loop on the next adjacent element, and means for attaching said rail-bond to the rail ends, substantially as set forth.

3. An electric rail-bond consisting of several connecting elements and means for attaching them to the rail ends, the said elements being provided with differently-spaced loops at points between the ends of the elements, and 50 said loops all being located on corresponding sides of the elements, that is to say, on corresponding sides of corresponding end portions of the elements, and being placed side by side and outside each other in a series extending 55 obliquely across the bond, substantially as set forth.

4. An electric rail-bond which consists of several connecting elements and means for attaching them to the rail ends, the elements being provided with loops bent out of the general direction of the elements and located also outside of each other or unnested, the said loops being further arranged at progressively-varying distances from the ends of the bond 75 so as to extend in a substantially oblique line relatively to one side of the bond, the intermediate ones of the said loops, each, with respect to the length of the bond, being located directly between two loops, and in contact, in 80 the endwise direction of the bond, with the loops between which they are located, substantially as set forth.

In testimony whereof I have hereunto set my hand, in the presence of two subscribing 85 witnesses, this 19th day of April, 1900.

JANG LANDSING.

In presence of—

E. P. WETMORE,
N. H. LANDSING.
